SIDE FRAME BRACKET

John E. Flesch and Eugene G. Opsahl, Chicago,
Ill., assignors to American Steel Foundries, Chi-
cago, Ill., a corporation of New Jersey

Application September 13, 1948, Serial No. 49,028

4 Claims. (Cl. 188—212)

1

This invention relates to railway car truck side frames and more particularly to a novel side frame casting comprising brackets adapted to support the end extensions of associated brake beams to guide the latter in their movement toward and away from the wheels of the truck.

A primary object of the invention is to devise a side frame casting wherein the brake beam support brackets are integrally cast in such manner as to strengthen the frame structure by providing secondary trusses.

A more specific object of the invention is to provide in a side frame, such as above described, a brake beam bracket having spaced ledges or webs extending along the inboard side of the tension member and merging with a flanged spring seat thereon to connect the flanged portion of the seat to an adjacent sloping portion of the tension member thereby providing secondary trusses.

Another object of the invention is to prevent entrapment of foreign matter, such as coal dust and dirt, at the rear end of the brake beam support bracket which is provided with a stop to positively limit the release movement of the associated beam away from its related wheel and axle assembly.

The foregoing and other objects and advantages of the invention will become apparent from a consideration of the following specification and the accompanying drawings, wherein:

Figure 1 is a fragmentary outboard side elevational view of a side frame embodying the invention, only one-half of the frame being shown with the journal end thereof broken away, inasmuch as the frame is symmetrical about its transverse center line;

Figure 2 is a sectional view on the line 2—2 of Figure 1;

Figures 2A and 2B are sectional views on the lines A—A and B—B of Figure 2;

Figure 3 is a sectional view in the horizontal planes indicated by the line 3—3 of Figure 2;

Figure 4 is a bottom plan view of the structure shown in Figure 1;

Figure 5 is a fragmentary sectional view taken on the line 5—5 of Figure 2;

Figure 6 is a fragmentary inboard side elevational view taken from the line 6—6 of Figure 2;

Figure 7 is a sectional view taken on the line 7—7 of Figure 6;

Figure 8 is a sectional view taken on the line 8—8 of Figure 6; and

Figures 9 to 11, inclusive, illustrate a modified form of side frame embodying the invention,

2

Figure 9 being a fragmentary inboard side elevational view corresponding to Figure 6, Figure 10 being a sectional view on the line 10—10 of Figure 9, and Figure 11 being a sectional view taken on the line 11—11 of Figure 9.

Describing the invention in detail and referring first to the preferred embodiment illustrated in Figures 1 to 8 inclusive, the frame comprises a compression member 2 and a tension member 4 merging adjacent each end of the frame with a column 6 defining a bolster opening 8 (Figure 1) and a window 10.

The compression member 2 is of box section above the bolster opening 8 and comprises top and bottom walls 12 and 14 and inboard and outboard walls 16 and 18.

The bottom wall 14 of the compression member merges with a transverse web 20 of each column 6, the column having inboard and outboard webs 22 and 24 merging respectively with the compression member walls 16 and 18 and beaded as at 26 around the margin of the window 10 to reinforce the structure. The column web 20 is provided at the inboard and outboard edges thereof with inboard and outboard ribs or lugs 28 and 30 and adjacent recesses 32 and 34 to accommodate an associated wear plate (not shown). The column is also provided with top and bottom lugs 38 and 40 and adjacent recesses 42 and 44 adapted to cooperate with the top and bottom margins of the plate.

Thus it will be understood that a wear plate may be seated against the inner surface of the column web 20 which is relieved as at 32, 34, 42 and 44 to insure a good seat for the plate which is centered between lugs 28, 30, 38 and 40 and is then welded into place, in any convenient manner, to provide a suitable friction surface for cooperation with an associated friction device (not shown), as will be readily understood by those skilled in the art.

The tension member 4, as best seen in Figures 2 and 8, is a box-section member having top and bottom walls 46 and 48 and inboard and outboard walls 50 and 52 as well as a center rib 54 connecting the walls 46 and 48 beneath the bolster opening 8. As best seen in Figure 8, the inboard and outboard tension member walls 50 and 52 merge with the lower ends of the respective column webs 22 and 24.

Beneath the bolster opening 8 the tension member web 46 is widened, at 56 and 58 (Figure 2) and is flanged as at 60 and 62 respectively, to afford positioning means for associated springs (not shown) supported on a spring seat 64 on the

upper surface of the wall 46 which is provided with spring positioning lugs 66. The flanges 60 and 62 are beaded as at 68 and 70 respectively, to strengthen the structure, the outboard flange 62 and bead 70 extending obliquely inwardly toward the longitudinal center line of the frame to merge with the related outboard column web 24 at a point disposed longitudinally beyond the spring seat 64 toward the end of the frame whereat the tension member webs 46 and 48 slope upwardly toward the end of the frame, as best seen in Figure 1.

A brake beam guide and support bracket, generally designated 72, is formed on the inboard side of the frame and comprises a top ledge 74 connected to the inboard column web 22 and extending diagonally upwardly toward the end of the frame along the inboard tension member wall 50. The lower or rear extremity of the ledge 74 merges with the bead 68 of the inboard spring seat flange 60, as best seen in Figure 6, and the upper or forward end of the ledge 74 is connected to a front wall 76 formed on the inboard side of the tension member web 50 and adapted to afford stop means limiting upward movement of an associated beam (not shown) as the latter is actuated to applied position with respect to the truck wheels (not shown).

The bracket 72 also comprises a bottom ledge 78 merging with the inboard edge of the spring seat extension 56 and extending diagonally upwardly along the inboard tension member web 50 to merge with the front wall 76 of the bracket. The ledge 78 is reinforced by a gusset 79 connected to the inboard tension web 50. The ledges 74 and 78 are formed at their upper or forward extremities with wheel recesses 80 and 82 respectively, adapted to receive the associated truck wheel (not shown) under certain operating conditions, as will be readily understood by those skilled in the art.

As best seen in the sectional view of Figure 7, the inboard tension member wall 50 and the front wall 76 of the bracket 72 are recessed as at 84 to accommodate an associated wear plate (not shown) and the ledges 74 and 78 are provided with perforations 86 and 88 respectively, to afford positioning means for said wear plate.

Figure 7 also shows the manner in which the spring seat flange 60 extends obliquely inboard toward the transverse center line of the frame from its juncture with the tension member web 50. The flange 60 affords a stop limiting release movement of the associated beam (not shown) as the latter slides downwardly in the bracket 72 away from the associated wheel. It may be noted that in certain types of service, foreign matter, such as coal dust and dirt, may collect in the bracket 72 and may tend to restrict release movement of the beam by lodging between the beam element within the bracket and the stop surface of the flange 60 at the rear end of the bracket. This is prevented in the above-described arrangement, due to the oblique formation of the flange 60 at the lower or rear end of the bracket which accommodates escape of such foreign material from the bracket as the beam moves rearwardly therein.

Another novel feature of the above-described arrangement is the manner in which the bracket ledges 74 and 78 merge with the spring seat flange 68 and with the upwardly sloping portion of the tension member 4, as best seen in Figure 6, thereby affording secondary trusses which

strengthen the tension member at its connection with the column 6.

Figures 9-11 illustrate a modification of the novel side frame wherein parts corresponding with those of Figures 1-8 are identified by corresponding numerals. In the modification of Figures 9-11, the top ledge 74 of the bracket 72 is terminated short of the spring seat flange 60 and is connected directly to the column web 22, as in the previously-described arrangement, but is additionally reinforced by a flange or gusset 100 integrally formed with the column web 22 and the upper surface of the ledge 74. The lower bracket ledge 78 is connected to the spring seat flange 60 and merges therewith at the lower edge of the beading 68 thereon. As in the previously-described arrangement, the flange 60 affords stop means at the rear end of the bracket 72 for limiting release movement of the associated beam therein and the flange 60 extends obliquely inboard from the tension member wall 50 toward the transverse center line of the frame, to facilitate escape of foreign material from the bracket 72, as above described in connection with Figures 1-8.

We claim:

1. A truss side frame comprising a column having inboard and outboard webs and a transverse wall, a compression member having top and bottom walls and having inboard and outboard walls merging with respective webs; a tension member comprising top and bottom walls and comprising inboard and outboard walls merging with respective webs, the top wall of said tension member having a widened portion at one side of said column defining a spring seat, inboard and outboard flanges upstanding from said portion, the top and bottom walls of said tension member having segments sloping upwardly beneath said column toward the end of the frame, a brake beam support bracket on the inboard side of said frame comprising top and bottom ledges sloping upwardly toward the end of the frame and merging with the inboard tension member wall between said sloping segments, said inboard flange having a portion affording a brake beam stop at the lower end of said bracket and extending obliquely from said transverse wall to the inboard edge of said seat to prevent entrapment of foreign material between said flange portion and an associated brake beam element within said bracket.

2. A frame, according to claim 1, wherein both ledges merge with the inboard flange, the top and bottom ledges merging respectively with the sloping segments of the top and bottom tension member walls to afford secondary trusses.

3. A frame, according to claim 1, wherein the bottom ledge merges with the inboard flange and with the sloping segment of the bottom tension member wall, and the top ledge merges with the top tension member wall and is spaced from said inboard flange, the lower end of said top ledge being provided with a gusset connected to the inboard column web.

4. A truss side frame comprising a column having inboard and outboard webs and a transverse wall, a compression member having inboard and outboard walls merging with respective webs, a tension member comprising top and bottom walls and comprising inboard and outboard walls merging with respective webs, the top wall of said tension member having a widened portion at one side of said column defining a spring seat, inboard and outboard flanges up-

standing from said portion, a brake beam support bracket on the inboard side of said frame comprising top and bottom ledges sloping upwardly toward the end of the frame, said inboard flange having a portion affording a brake beam stop at the lower end of said bracket and extending obliquely from the inboard column wall to the inboard edge of said seat.
